SPEED REGULATOR

Iner J. Larson, Oaklyn, and John J. Hoehn, Camden, N. J., assignors to Radio Corporation of America, a corporation of Delaware

Application December 9, 1932, Serial No. 646,512

3 Claims. (Cl. 188—187)

This invention relates to speed regulators, and more particularly to speed regulators adjustable to one or the other of two positions, such as are used on phonographs or spring-driven motion picture cameras.

In such devices it has heretofore been customary to provide an indicator plate or stop-plate on the camera case, and in order that the proper speeds might be secured it was necessary that either the indicator or stop-plate be adjustable, or that there be an adjustment between the control knob and the governor itself. Both of these arrangements were undesirable, as they are likely to get out of adjustment, were difficult to adjust, and were expensive.

In our invention, an adjustable stop member is fixed to the control knob and is arranged to be locked thereto in adjusted position, and the disadvantages hereinbefore stated are thereby avoided.

One object of our invention is to provide an improved speed regulator which can be easily shifted from one of two predetermined speeds to another.

Another object of our invention is to provide an improved speed regulator which is inexpensive to manufacture and assemble but which is nevertheless accurate.

Another object of our invention is to provide such a device having a positive stop at each of two predetermined positions.

Another object of our invention is to provide such a device having a stop member which is readily adjustable.

In the drawing:

Figure 1 is a front view of the control-knob and stop-plate.

Figure 2 is a side view, partly in section, of our adjusting device as applied to the governor of a camera or phonograph.

Figure 3 is an exploded view showing the relation of the adjustable stop to the control knob.

The control knob, indicated at 1, preferably lies with its face slightly below the face of the camera-case (or other casing of the apparatus) 2, and is made in the form of an ordinary screw-head with the slot therein of sufficient size so that the knob may be actuated by the insertion of the edge of a coin or the like.

The adjustable stop-plate, indicated generally at 3, is loosely mounted on the spindle 10 and lies against the back of the head 1, and the projecting tongue thereof extends upwardly past the head 1 into the annular recess 4.

This recess 4 is provided with two shoulders 5

and 6 against which the tongue of the member 3 strikes to stop it in predetermined positions.

The adjusting knob is provided with a spindle 10 which passes through an appropriate aperture in the frame member 18, and at the end of this spindle is a reduced portion 11 having a screw thread. This screw thread fits into a corresponding thread in the member 12, so that rotation of the knob 1, causing rotation of the portion 11, causes a movement of the member 12 axially of the screw. The member 12 is prevented from rotating by a slot 13 therein which slides longitudinally upon the pin 14.

A rather stiff spring 15 surrounds the spindle 10 and bears against the frame member 18 and the member 12 and thereby maintains the adjusting knob 1 firmly in contact with the stop member 3, and causes this stop member to bear firmly against the washer 7 on the frame member 18 thereby accurately defining the position of the member 12.

Inserted into the member 12 is the usual fibre-plug or the like 16 which is adapted to cooperate with the plate 17 of the governor when the speed of the device becomes too great and to provide a braking effect thereupon, thereby maintaining the speed at the proper point.

It will be apparent that rotation of the knob 1 from the point where the member abuts against the stop 6 to the point where the member 3 abuts against the stop 5 will cause a certain change in the speed of the apparatus, and the range of this speed variation can be accurately predetermined by the pitch of the screw 11, the stiffness of the springs of the governor and the weight of the fly-balls of the governor. On the other hand the exact points at which these stops would function cannot readily and accurately be predetermined on account of the necessary manufacturing tolerances in, for example, the thickness of the plate 17, the point circumferential of the member 11 at which the screw thread starts, the length of the shoulder 10, the thicknesses of the members 3 and 7, etc. It is therefore necessary that a relative adjustment be provided between the adjustable stop member 3 and the brake member 16 so that when the member 3 is against either the shoulder 5 or the shoulder 6 the apparatus will operate at the desired speed.

It will be seen from Fig. 3 that the back of the knob 1 is provided with a plurality of radial grooves 8, while the member 3 is provided with four radial ridges indicated at 9 of such shape as to cooperate with the grooves 8. When the device is assembled in the relation shown in

Fig. 2, at least one pair of these radial ridges on the member 3 will fit into the radial grooves in the member 4 and will be maintained firmly therein by the action of the spring 15. In order to accomplish the adjustment hereinbefore mentioned, the knob 1 is rotated until the member 3 is against either the shoulder 5 or the shoulder 6 depending on which speed is to be measured, and the speed of the apparatus is then measured or otherwise checked against the standard. It will be apparent that if the thread on the member 11 is a right-hand thread, then rotation of the knob 1 in a clockwise direction will decrease the speed, and rotation of the knob 1 in a counter-clockwise direction will increase the speed, wherefore the stop indicator 5 will indicate a high speed and the stop indicator 6 will indicate a lower speed. If with the member 3 against the stop 5 the speed is not sufficiently high, the knob 1 is forced to rotate still further in the counter-clockwise direction until the speed reaches the proper amount. This rotation can be forced without damaging the member 3 since, on the application of sufficient pressure, the spring 15 will yield and the corrugations 8 will ride over the ridges 9 until such excess pressure is discontinued when these parts will be retained against further relative movement by the action of the spring 15. If in the position 5 the speed of the device is too high, the knob is rotated until the member 3 strikes the stop 6 and is then further rotated by an appropriate amount, whereupon it can again be rotated until the member 3 strikes the stop 5 to check the speed at this point. If the speed is measured at the position 6, the reverse procedure would be used.

This invention is particularly useful in connection with motion picture cameras of the "amateur" or "16 mm." type since in such cameras it is sometimes desirable to take silent pictures which normally operate at sixteen frames per

second, while when it is desired to take sound films it is necessary that the film be operated at the standard speed of twenty-four frames per second. In this instance, the device would be so constructed that at the position 5 the camera would run at twenty-four frames per second, at position 6 it would run at sixteen frames per second. When applied to such a camera the member 2 would ordinarily be the side of the camera case.

It will be apparent that our invention can be applied to any analogous apparatus intended to operate at two different predetermined speeds.

Having thus described our invention;

We claim:

1. Adjusting means for speed control apparatus comprising an adjusting knob, a spindle mounted upon said adjusting knob, a stop member loosely mounted upon said spindle and rotatable therewith, the adjacent faces of said knob and stop member having inter-engaging teeth and means for yieldably retaining said teeth in engagement.

2. Means for stopping the rotation of a member rotatable through a portion only of a revolution at a predetermined point comprising a fixed stop upon a stationary member adjacent said rotatable member, and a stop member adapted to cooperate with said fixed stop and rotatable with the said member, and means for maintaining said movable stop rigidly in predetermined relation to said rotatable member under normal operating pressures but yieldable under excessive pressures.

3. In combination, a rotatable control knob, an index member, inter-engaging teeth upon said control knob and said index member, and spring means maintaining said teeth in engagement whereby said knob and said index member are normally rotatable as a unit but are relatively adjustable.
